No. 826,811.

PATENTED JULY 17, 1906.

J. D. CANN.
COMBINATION GAGE.
APPLICATION FILED DEC. 14, 1905.

UNITED STATES PATENT OFFICE.

JAMES DANIEL CANN, OF NEW CASTLE, PENNSYLVANIA.

COMBINATION-GAGE.

No. 826,311.

Specification of Letters Patent.

Patented July 17, 1906.

Application filed December 14, 1905, Serial No. 291,672.

To all whom it may concern:

Be it known that I, JAMES DANIEL CANN, a citizen of the United States, and a resident of New Castle, in the county of Lawrence and State of Pennsylvania, have invented a new and Improved Combination-Gage, of which the following is a full, clear, and exact description.

The purpose of the invention is to provide a combination-tool or universal machinist's tool whereby the gage, bevel, or angle of any piece of work may be quickly and accurately determined; and the purpose of the invention is to construct such a tool of three main elements capable of use independently or in combination.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the improved tool complete. Fig. 2 is also a plan view of the tool and illustrates the association of the protractor-plate and the gage star-wheel only. Fig. 3 is a view similar to that shown in Fig. 2, but illustrates the association of the protractor-plate and the gage-arm; and Fig. 4 is an enlarged transverse section taken practically on the line 4-4 of Fig. 1.

A represents the body-plate of the tool, the said body-plate being L-shaped in general contour, embracing two limbs *a* and *a'*. In the end of one of the said limbs—the limb *a'*, for example—a V-slot 10 is made, adapted as a gage for setting thread-tools for chasing threads, and the corners 11 of the said body-plate A are rounded off, giving five different fillets.

A protractor-scale 12 is produced on the limb *a* of the said body-plate, extending longitudinally of the said limb, the straight edge of the scale facing the opposing limb *a'*, and at the point from which the arc of the scale 12 is struck an opening 13 is made in the said body-plate to tightly receive a bolt 14, over the threaded portion of which bolt a washer 15 is placed, and the threaded end of the bolt is capped by a milled nut 16, as is best shown in Fig. 4.

A gage-wheel B is mounted to turn loosely on the said bolt 14, and said wheel is a star-

wheel, being usually provided with six points 17. The edge of the wheel between the said points is concaved, as is shown at 18 in the drawings. When the gage-wheel B is properly mounted on the bolt 14, it can be readily turned around the said bolt, and the points on the wheel will move over the protractor and will register with the side edges of the limbs of the body-plate where the limbs meet. The points on the wheel produce six equal divisions thereon, thus producing six different fillets; but the size of the wheel is made corresponding to the size of the body-plate and more than six points may be provided for the wheel. The curved spaces between the points of the wheel serve also as fillets when the wheel is used independently of the body-plate.

The third piece in the make-up of the tool consists of a gage-arm C, and it may be here remarked that the three parts A, B, and C are made from thin metal, preferably steel, and are flat on both faces. The gage-arm C has one end offset from the other, producing thereby two limbs *c* and *c'*, the limb *c* being longer than the limb *c'*, and a longitudinal slot 19 is made in the said gage-arm, extending from the bridge or intermediate section *c*², connecting the two limbs *c* and *c'* into the longer limb *c* for a predetermined distance. When the gage-arm is in position, the threaded stud or bolt passes through the said slot, rendering the arm adjustable on the body-plate. The star-wheel can be used alone as a female radius-gage for obtaining fillets in any bored hole or for analogous purposes, and the said gage or star-wheel B is many times used, as shown in Fig. 2, in connection with the protractor-plate A, as a radius or fillet gage for obtaining fillets in any turned work, for instance.

The complete gage, as shown in Fig. 1, is likewise used for many purposes—as, for example, the gage-arm C, in connection with the rest of the parts, may be employed for finding the center of any round or square piece of work and will also show a special mark or protractor. Again, the gage-arm C may be used directly with the body or protractor plate A, as shown in Fig. 3, wherein the gage-arm C is employed as a bevel-gage and may be used with or without a protractor, giving slight angles which cannot be given with the protractor alone.

It will be understood that the protractor may be provided with special marks, desig-

nating, for example, center gage, center square, hexagon gage, &c., and that scales or lines for such gages may be produced both upon the body and upon the gage-wheel wherever found necessary.

5 The gage-arm C may be used as a bevel for shaping or planing hexagon nuts, &c., or as a center gage or a bevel or depth gage, and the body or protractor plate may be used alone 10 in like manner as a T-square.

This tool is capable of many arrangements for different work and, in fact, will answer as a machinist's gage wherever such gage is needed.

15 The limbs *c* and *c'* of the gage-arm C are offset, as shown, so as to bring the threaded stud or bolt 14 centrally, making the center square and protractor perfect. The gage-arm C has one pointed end 20 to be used in 20 dovetailing and for cutting bastard-threads or for cutting into sharp corners.

The gage-arm C is provided with a scale 21 in inches and fractions of inches, which scale is read at the outer longitudinal edge of the 25 longer limb *c* of said arm.

25 With reference to Figs. 1 and 2 it will be observed that the spaces between the points 17 of the gage star-wheel B are the same and that the distance between opposing points is such that when one of the said points is at 30 the inner longitudinal edge of the limb *a* of the body-plate A the opposing edge of the opposing point will be at the inner longitudinal edge of the limb *a* of the said body or protractor plate.

35 Having thus described my invention, I claim as new and desire to secure by Letters Patent—

1. A machinist's tool, consisting of an angular body-plate comprising two limbs at angles to each other having a protractor upon one of its limbs, and a gage-wheel in the form of a star mounted to revolve on the said body-plate at a point from which the arc of the protractor is struck, said gage-wheel being also mounted so that in its revolution while 45 sundry of its points pass over the protractor other of its points pass over the inner edge of the said body-plate, or the edge where its 50 limbs meet.

2. A machinist's tool, consisting of an L-shaped plate having rounded corners and a protractor thereon, a gage-wheel in the form of a star, which gage-wheel is mounted to revolve on the said body-plate, the edge of the 55 said wheel between the points being concaved and the width of the spaces between the points being the same.

3. A machinist's tool, consisting of an angular body having a protractor thereon, and 60 a gage-arm having one end offset from the other, a longitudinal slot extending in one of the said end portions and into the connecting-section of the two end portions, and a bolt fitted tight to the body and passed 65 loosely through the said slot at a point from which the arc of the protractor is struck.

4. A machinist's tool consisting of an angular body-plate having a protractor thereon, a star-wheel mounted to revolve on the 70 said body-plate, the points whereof extend over the protractor, and a gage-arm adjustable upon the said body-plate, acting in conjunction with the said star-wheel.

5. A machinist's tool, comprising an angular body-plate having rounded corners and a protractor thereon, the said body-plate having a recess in one of its ends, a pivot-pin passed through the said body-plate at the point where the arc of the said protractor is 80 struck, a gage-wheel in the form of a star, mounted to revolve upon the said pivot-pin, the points of the gage-wheel extending across the protractor, and a gage-arm having one end offset from the other, providing a long 85 and a short limb, the short limb being pointed and the long limb provided with a scale, said gage-arm being likewise provided with a slot produced in the longer limb of the arm and extending into the section connecting 90 the two limbs, and a locking device for the gage-wheel and for the gage-arm, for the purpose described.

6. A machinist's tool consisting of a substantially L-shaped plate having a protractor thereon, and a star gage-wheel mounted to revolve on the said plate, the points of the wheel traveling over the protractor and moving relatively to the point of juncture of the limbs of the plate.

7. A machinist's tool, consisting of a substantially L-shaped plate having a protractor thereon, and a star-shaped gage-wheel mounted to revolve upon the plate, having curved surfaces between its points, the points traveling over the protractor, and the curved surfaces between the points bridging, in the revolution of the wheel, the point of juncture between the limbs of the plate.

In testimony whereof I have signed my name to this specification in the presence of two subscribing witnesses.

JAMES DANIEL CANN.
